C. S. BARON

LIQUID CONTAINER AND TOP THEREFOR

Filed May 29, 1924

Inventor:
Charles S. Baron,

By Atkins & Atkins,

Attorneys.

Patented Dec. 22, 1925.

1,566,573

UNITED STATES PATENT OFFICE.

CHARLES S. BARON, OF TIFFIN, OHIO.

LIQUID CONTAINER AND TOP THEREFOR.

Application filed May 29, 1924. Serial No. 716,691.

To all whom it may concern:

Be it known that I, CHARLES S. BARON, a citizen of the United States of America, and resident of Tiffin, in the county of Seneca, in the State of Ohio, have invented certain new and useful Improvements in Liquid Containers and Tops Therefor, of which the following is a specification, reference being had to the accompanying drawing.

10 My invention relates to liquid containers and more particularly to the same intended for table service commonly known as cans, jugs, or pitchers, provided, in each instance, with a spring-actuated cover for opening and closing the same in use.

15 The object of my invention is to produce, by way of improvement of such containers, an exceedingly simple device for the purpose indicated, and one wherein the cost of manufacture is reduced substantially to a minimum without impairment of the durability of the article and also its efficiency particularly from a sanitary point of view.

20 What constitutes my invention will be 25 hereinafter specified in detail and succinctly set forth in the appended claim.

25 In the accompanying drawing, I illustrate my invention in present preferred form of embodiment, with suggestion of one or 30 two of the many formal modifications of such embodiment as would naturally suggest themselves, and which are, therefore of course, contemplated within the scope of my invention.

35 In said drawing,

Figure I is a side elevation of the upper portion of a container with its top applied thereto, said top being shown by full lines in the closed position, and by dotted lines in 40 the open position.

Figure II is a view similar to Figure I, but taken at right angles thereto and looking at the container from the handle-supporting side thereof.

45 Figure III is a vertical medial section of Figure II.

Figure IV is a rear elevation of the top shown in Figure II, detached, and illustrative of my method of forming the clamping jaws thereof by slits formed in the skirt of the top.

50 Figure V shows, in manner similar to Figure I, a slight modification of the invention in respect to form of the container handle.

55 Figure VI shows in like manner a further modification.

Referring to the numerals on the drawing, 1 indicates a container body, which may be made of any suitable material, preferably glass, and of any preferred shape and dimensions.

60 It is provided on one side with a handle 2, and upon the opposite side therefrom with a pouring spout 3, which preferably consists, in effect, of an expansion of the mouth or open end of the container.

65 The upper edge 5 of the body is in the same plane with the upper edge of the spout 3, both being parallel to the horizontal plane, as of a table top support.

70 The body 1 is characterized by the presence, upon the handle-supporting side of it, of a cover-engaging member 7. Said member may be a part of the handle 2 itself, as shown in Figures I and V, for instance, or it may be a separate block of glass 8, as shown in Figure VI. The choice of the kind of member 7, will depend, in part, upon whether, in manufacture, the handle is molded on the body, in the making of the body, or whether it is "stuck" on it afterwards.

75 The body 1, being provided as aforesaid with a suitable member 7 of any sort, is provided on its handle side with a neck 9, that is to say, with an external surface of regular conformation which is, at least in part, preferably cylindrical. Over the top of the neck fits a fixed portion 10 of a cover, which includes, besides the portion 10, a 80 lid 11 hinged thereto in any usual manner, for example that indicated at 12. A thumb-handle 15 projects upwardly and rearwardly from the lid 11, and preferably constitutes a guard to a spring 16, coiled, in any usual way common in the art, about the pintle pin 17 which operatively unites the parts 10 and 11 of the cover.

85 In the fixed portion 10 of the cover, in conjunction with a body 1 adapted substantially as specified for its accommodation, are found the distinctive features of my invention.

90 They include a skirt 18 on the cover-portion 10, which being composed of resilient metal is made to clamp, with snug fit and frictional engagement, upon the outside of the neck 9. The medial rear portion of the skirt 18 is provided with an opening made to receive and hold with snug fit the member 7. To that end, I prefer to 95 form in the sheet metal of which the skirt 100

110

18 is preferably made two intersecting slits 19 and 20, one vertical and the other horizontal. The portion of the skirt divided by the slit 19 and measured by the length of the slit 20 is afterwards, along lines 21 parallel to the line of the slit 19, bent outwardly so as to form jaws 23 and 24. Said jaws are made to fit the opposite side walls of the member 7, and may suffice, through frictional contact only, to hold the cover-portion 10 in substantially fixed relationship thereto.

The function of the jaws 23 and 24 is two-fold. They not only serve to hold the cover-portion against any coaxial movement about the neck 9, but also to prevent disengaging movement of the skirt 18 rearwardly upon the neck 9. In respect to the latter function, I prefer also to provide, besides frictional engagement, means for positive engagement of the jaws with the member 7. In that regard, the opposite sides of the member 7 may be provided with skirt-engaging means, such, for example, as shallow grooves or scores 25 adapted to take in inverted lips 26 on the respective jaws; or, to the same effect, the member 7 may be provided with shoulders 28 which define between them and the neck 9 shallow vertically disposed recesses for the snug reception of the jaws, as shown for example in Figure V.

The skirt 18 extends, at its opposite ends, beyond the superposed pintle-pin 17, as indicated at 30.

35 The operation of my invention may be briefly described as follows.

The body 1 being provided of the shape desired, a cover is selected to correspond thereto, and they are assembled by slipping

the skirt 18 of the cover-portion 10 upon the neck 9. Effectual engagement between the neck 9 and the ends of the two parts of the said skirt, divided as specified by the presence in it of the rearward medial opening therein, preferably flanked by the jaws 23 and 24, is accomplished by the assemblage described. Afterwards, pressure upon the thumb-handle 15 will serve to open the lid 11 against the resistance of the spring 16, as often as occasion demands. In that connection, let it be noted that said pressure has the effect of perfecting and maintaining the assemblage of the body 1 with the portion 10 of the cover, the extension of the ends of the skirt 18, as indicated at 30, being sufficient to limit the relative movement of the lid 11, and to prevent any tendency of the spring 16 to lift the part 10, which might otherwise occur through the actuation of the spring in closing the lid 11.

What I claim is:

A container comprising a body having an exterior lateral projection adjacent its upper end, a relatively stationary cover section having a depending marginal skirt, of substantially U-shape, embracing the body, a substantially T-shaped slit being formed in said skirt and extending through the lower edge thereof and the portions separated from the body of the skirt by said slit being bent outward to provide two members, separated throughout their length, engaging opposite sides of said projection on the container body, and a movable cover section hinged to said stationary section.

In testimony whereof, I have hereunto set my hand.

CHARLES S. BARON.
